UNITED STATES PATENT OFFICE

2,436,193

LID OPENER FOR CONTAINERS

John Winnington Bristow, Birmingham, England,
assignor of one-half to Arthur Bertram Cole,
Junior, Beckenham, England

Application March 26, 1946, Serial No. 657,127
In Great Britain February 3, 1945

6 Claims. (Cl. 220—43)

1

This invention relates to hollow containers, cans, tins and the like, particularly of the kind having a flanged lid which is adapted to be secured in position when pressed into the upper end of the container.

Containers of this character usually possess the disadvantage that when it is desired to open the container the lid cannot be removed without the use of some external instrument or tool, such as a screw-driver, by which the flanged lid must be levered up and loosened from the body of the container.

According to the present invention, however, a hollow container is provided having a flanged lid adapted to make tight contact with the container and rotatably mounted means which is adapted to bring about the interengagement of co-operating members provided on the container and lid respectively, so as to cause said lid to be loosened from the container.

According to the preferred arrangement, the aforesaid means preferably comprises an annular member rotatably mounted on the end of the container adapted to receive the lid, said annular member being provided with one or more projections or raised portions which are adapted to co-operate with corresponding projections or indentations on the said lid.

This annular member preferably comprises a ring having an inwardly projecting flange which carries said projections or raised portions and is disposed immediately below the flange of said lid whereby rotation of said ring causes said projections or raised portions to engage with the projections or indentations formed on the flange of the lid so as to cause the lid to be pushed upwards.

The invention will be more completely understood from the following detailed description which is given in conjunction with the accompanying drawings, in which

Figure 1 shows a plan view of the lid of a container constructed in accordance with the invention;

Figure 2 shows a sectional view of the container with the lid mounted in the closed position;

Figure 3 shows a sectional view of the upper portion of the container with the lid in the loosened position; and

Figure 4 shows a plan view of the container with the lid removed.

Referring now to these drawings, the container consists of a hollow metal can or tin 1, of cylindrical shape having a lip or beading 2 at the open end and an inwardly projecting flange 3 into

2

which the base 4 of the lid is adapted to fit so as to make tight contact. Rotatably mounted on the lip or beading 2, is a ring member 5 which is located in position on the container by bending or crimping its lower edge in such a way that it curls over the lip or beading 2. The ring member is thus permanently secured to the container but is free to rotate on the container about its longitudinal axis. This ring member has an inwardly projecting flange 6, which substantially covers the flange 3, and makes contact with it. This flange 6, is provided on its upper side with three equally spaced upstanding raised members 7, these members being of wedge-shaped formation with inclined faces, the thickest portion being at the centre. The outside of the ring member 5, is preferably knurled and may be suitably marked to indicate that this ring should be rotated in order to raise the lid. The latter has an outwardly projecting flange 8, which substantially covers the flange 6, when the lid is in the closed position on the container, and this flange 8 is provided with three equally spaced projections or indentations 9, which project downwards and make contact with the upper surface of the flange 6, when the lid is pressed into the closed position, the lid being so positioned that these downwardly projecting indentations 9 are disposed at points intermediate the upstanding raised members 7, on the flange 6.

It will be seen that with this arrangement when it is desired to loosen or remove the lid, if the ring member 5 is rotated in either direction the sloping faces of the raised members 7, carried by the flange 6, will engage with the downwardly projecting indentations 9 on the flange of the lid and that if rotation of the ring member 5 is continued, these raised members 7 will slide under the indentations 9 and cause the lid to be forced upwards whence it may be readily removed without difficulty.

This arrangement has the advantage that no external instrument is required to remove the lid and, furthermore, the lid after being removed may be replaced and again removed as often as desired without detriment to the form or shape of the lid.

It is to be understood, however, that the invention is not to be regarded as being limited to the particular construction hereinbefore described, and that it is capable of many and varied modifications. For example, while it is preferred to provide the ring member and the lid with three co-operating members for loosening the lid when the ring member is rotated, it is to be understood

that any convenient number of such members may be provided as desired. Furthermore, the ring member for loosening the lid may, if desired, be inverted and rotatably mounted on the lid instead of on the container and in this case the ring member would be arranged to carry one or more downwardly projecting members which would engage with corresponding upstanding raised members provided on the flange of the container which carries the lid.

We claim:

1. Hollow container comprising a cylindrical body portion having an open end, an inwardly projecting flange formed on said body portion at said open end, a circular flanged lid adapted to fit into said open end so as to make tight contact with said flange, a beading formed on said body portion round the open end thereof, an annular member rotatably mounted on said beading, said annular member also having an inwardly projecting flange disposed between the flanges formed on said lid and said body portion respectively, when said lid is in the closed position, a set of downwardly extending projections on the flange of said lid, and a set of upstanding projections on the inwardly projecting flange of said annular member disposed intermediate the projections on the flange of said lid, whereby rotation of said annular member causes said upstanding projections to slide under said downwardly extending projections so as to cause said lid to be pushed upwards.

2. Hollow container comprising a cylindrical body portion having an open end, an inwardly projecting flange formed on said body portion at said open end, a circular flanged lid adapted to fit into said open end so as to make tight contact with said flange, a beading formed on said body portion round the open end thereof, an annular member rotatably mounted on said beading, said annular member also having an inwardly projecting flange disposed between the flanges formed on said lid and said body portion respectively, when said lid is in the closed position, a set of downwardly extending indentations on the flange of said lid, and a set of raised members on the inwardly projecting flange of said annular member, disposed intermediate said downwardly extending indentations, whereby rotation of said annular member causes said raised members to slide under said downwardly extending indentations so as to cause said lid to be pushed upwards.

3. Hollow container comprising a cylindrical body portion having an open end, a flange formed on said body portion at said open end, a circular flanged lid adapted to fit into said open end so as to make tight contact with said flange, an annular member rotatably mounted on a locating guide on said body portion, said annular member having an inwardly projecting flange disposed between the flanges formed on said lid and said body portion respectively, a set of downwardly extending projecting members disposed on the flange of said lid and a set of upstanding projecting members disposed on said inwardly projecting flange, whereby rotation of said annular member causes said set of projecting members on said in-

wardly projecting flange to slide under said set of projecting members on the flange of said lid, so as to cause said lid to become loosened.

4. Hollow container comprising a cylindrical body portion having an open end, a flange formed on said body portion at said open end, a circular flanged lid adapted to fit into said open end so as to make tight contact with said flange, an annular member rotatably mounted on a locating guide on said body portion, said annular member having an inwardly projecting flange disposed between the flanges formed on said lid and said body portion respectively, a downwardly extending projecting member disposed on the flange of said lid and an upstanding projecting member disposed on said inwardly projecting flange, whereby rotation of said annular member causes the projecting member on said inwardly projecting flange to slide under the projecting member on the flange of said lid so as to cause said lid to become loosened.

5. Hollow container comprising a cylindrical body portion having an open end, a flange formed on said body portion at said open end, a circular flanged lid adapted to fit into said open end so as to make tight contact with said flange, a rotatably mounted annular member having an inwardly projecting flange disposed between the flanges formed on said lid and said body portion respectively, a set of downwardly projecting members disposed on said inwardly projecting flange, and a set of upstanding projecting members disposed on the flange of said body portion, whereby rotation of said annular member causes said set of projecting members on said inwardly projecting flange to slide over said set of projecting members on the flange of said body portion so as to cause said lid to become loosened.

6. Hollow container comprising a cylindrical body portion having an open end, a flange formed on said body portion at said open end, a circular flanged lid adapted to fit into said open end so as to make tight contact with said flange, a rotatably mounted annular member having an inwardly projecting flange disposed between the flanges formed on said lid and said body portion respectively, a downwardly projecting member disposed on said inwardly projecting flange, and an upstanding projecting member disposed on the flange of said body portion, whereby rotation of said annular member causes said projecting member on said inwardly projecting flange to slide over said projecting member on the flange of said body portion so as to cause said lid to become loosened.
